UNITED STATES PATENT OFFICE.

WALTER MARTIN MUSGRAVE, OF BOLTON, ENGLAND.

DEVICE FOR LUBRICATING ENGINES.

SPECIFICATION forming part of Letters Patent No. 628,279, dated July 4, 1899.

Application filed January 16, 1899. Serial No. 702,337. (No model.)

To all whom it may concern:

Be it known that I, WALTER MARTIN MUSGRAVE, a subject of the Queen of England, residing at Bolton, in the county of Lancaster, England, have invented certain new and useful Improvements in Devices for Lubricating Engines, of which the following is a specification.

- This invention relates to improvements in
10 the construction of vertical compound steam-
engines and in apparatus for automatically
lubricating the same and is designed and
arranged in a compact and self-contained
manner.
15 On a framework of box form is mounted an
inclosed stand or frame provided with a door
or cover secured in any convenient manner.
On the upper end of the said stand or frame
are mounted the high - pressure and low-
20 pressure cylinders, provided with piston-
valves and valve-boxes, by which the cylinders
are brought into close proximity with each
other. Inside the stand or frame are disposed
slide-bars, on which are mounted slide-blocks
25 connected with the head of each piston-rod.
The piston-rods are coupled to balanced sweep-
cranks by connecting-rods. The crank-shaft
is mounted in side and middle bearings and
is provided at one end with what is well known
30 as a "crank-shaft governor" for regulating
the speed of the engine. If desired, any other
suitable governor may be employed for oper-
ating a throttle-valve. The valve-spindles
and piston-valves are operated by eccentric
35 and rods from the crank-shaft. The latter
is provided with a fly-wheel or a strap or rope
pulley for transmitting power by belt or ropes,
or the crank-shaft may be coupled direct to
any machine. The crank-shaft governor and
40 the eccentrics for operating the valves are in-
closed in stationary boxes or covers contain-
ing oil or lubricant.

My improved apparatus for automatically
lubricating the movable parts, wearing-sur-
45 faces, and the like of vertical engines con-
sists in providing the base or foundation plate
with an oil well or reservoir in which is lo-
cated a pump, the ram of which is actuated
50 by an eccentric and rod or other mechanical
means from the crank-shaft. The pump is fit-
ted with valve-boxes and valves on the ball or

other principle. The oil or lubricant is raised
from the well or reservoir and forced through
pipes to a box or chamber, which is provided
on each side with a parallel motion consisting
55 of pipes and couplings to compensate for the
vertical movements of the cross-head, to which
the same is attached. The oil or lubricant
is forced into the cross-head pin on one side
to lubricate, from whence it is forced by the 60
pump out on the other side and down pipes
connecting the same with the crank-pin. In
lieu of the before-mentioned parallel motion
I insert in each slide-bar a pipe-coupling by
means of a passage with the surface of the 65
slide-bars, and by the movements of the slide-
block of the cross-head the surplus oil or lu-
bricant is admitted through an opening to
the center pin of the cross-head, attaching
the connecting-rod thereto, from whence the 70
oil or lubricant flows down a pipe to the crank-
pin. To the main pipe leading from the oil-
pump are coupled other pipes, from which
oil or lubricant flows to the crank-shaft bear-
ings, the surplus flowing back to the oil well 75
or reservoir to be used over again. For the
purpose of lubricating the eccentric for pump
and other parts suitable "drip" pipes and
taps may be employed. The eccentric may
be lubricated by oil or lubricant which flows 80
from the crank-shaft pedestal coming in con-
tact with suitable openings and a plate se-
cured to the eccentric-ring. The pipes are
fitted with union joints and couplings where
necessary for the purpose of fixing or remov- 85
ing the same when desired or necessary. The
crank-shaft and other parts are provided,
where necessary, with dripping-points to pre-
vent oil or lubricant being drawn or forced
outside the framing, thus insuring outside 90
cleanliness.

Figure 1 is a longitudinal sectional eleva-
tion of my improvements in the construction
of vertical compound steam-engines and in
apparatus for automatically lubricating the 95
same; Fig. 2, a transverse sectional elevation
through line A B in Fig. 1; Fig. 3, a longitu-
dinal outside front elevation of Fig. 1; Fig.
4 a longitudinal sectional elevation of my im-
provements in the construction of vertical 100
compound steam-engines and in apparatus
for automatically lubricating the same, and

Fig. 5 is a transverse sectional elevation through line C' D' in Fig. 4.

In all the figures the same letters are employed to indicate corresponding parts.

5 C is the high-pressure cylinder; D, low-pressure cylinder; E, high-pressure-cylinder piston-rod; G, low-pressure-cylinder piston-rod; H, connecting-rods; I, balanced sweep-cranks; J, crank-pins; K, crank-shaft; L, 10 crank-shaft pedestals; M, fly-wheel; N, eccentrics; O, eccentric-rods; P, valve-spindles; Q, valve-boxes, and R foundation or framework of box form.

On the foundation or framework R is mounted 15 the inclosed stand or frame S, provided with the door or cover T, secured in any convenient manner. On the upper end of the stand or frame S are mounted the high-pressure cylinder C and the low-pressure cylinder D, provided with the valve-boxes Q, the latter being fitted with the piston-valves U. The valve-boxes Q are disposed on the outside, by which the steam-cylinders C and D are brought into close proximity with each 20 other. Inside the stand or frame S are disposed the slide-bars V, on which are mounted the slide-blocks W, connected to or formed with the heads X of the piston-rods E and G. The piston-rods E and G are coupled to

25 the balanced sweep-cranks I and crank-pins J by the connecting-rods H. The crank-shaft K is mounted in the side or middle bearings or pedestals L, being held therein by the caps Y, secured by bolts. The valve-spindles P 30 and piston-valves U are operated by the eccentrics N and eccentric-rods O from the crank-shaft K. The latter is fitted with the fly-wheel M, which may be substituted by a strap or rope pulley for transmitting power by

35 belts or ropes, or the crank-shaft K may be coupled direct to any machine by means of the shaft a and coupling b bolted to the boss or center c of the fly-wheel M, as shown in Figs. 1, 3, and 4 in the annexed drawings. 40 The eccentrics N for operating the piston-valves U are inclosed in the stationary boxes or covers d, secured by bolts or their equivalents to the sides of the stand or frame S and the foundation or framework R.

45 My improved apparatus for automatically lubricating the movable parts, wearing-surfaces, and the like of vertical engines consists in providing the foundation or framework R with the oil well or reservoir f, in 50 which is located the pump h, the ram j of the same being actuated by the eccentric l and rod m from the crank-shaft K. The pump h is fitted with the valve-box n, provided internally with valves on the ball or other principle. The oil or lubricant is drawn from the oil well or reservoir f through the suction-pipe p into the valve-box n by the outward stroke of the ram j and forced from the same by the downward stroke, which forces the oil 55 or lubricant up the pipe r and through the valve t into the pipes v, connected with the

caps or covers Y of the crank-shaft pedestals L. The pipes v are provided with the couplings x, secured to the under side of the slide-bars V and in line with the passage w, leading to the slide-blocks W on the slide-bars V; and as the slide-blocks W slide or move up and down the oil or lubricant is forced through the hole or passage a² into the cross-head pin b² to lubricate the center b², from whence the 70 oil or lubricant is forced by the action of the ram j of the pump out through and down the pipes z, connecting the same with the crank-pins J. By this arrangement the surplus oil or lubricant flows back to the oil well or reservoir f to be used over again, the operation being continuously repeated as long as the engine is in motion. The crank-shaft K is provided with the dripping-points s, turned or formed thereon to prevent oil or lubricant 75 being drawn or forced outside the framing of the engine.

The arrangement of my improved apparatus for lubricating the aforesaid movable parts by means of a parallel motion, as shown 80 in Figs. 4 and 5, consists in providing the foundation or framework R with the oil well or reservoir f, in which is located the pump h, the ram j of the same being actuated by the eccentric l and rod m from the crank-shaft 85 K. The pump h is fitted with the valve-boxes n, provided internally with valves on the ball or other principle. The oil or lubricant is drawn from the oil well or reservoir f through the suction-pipe p into the valve-box n by the 90 outward stroke of the ram j and forced from the same by the downward stroke of the ram, which action forces the oil or lubricant up the pipe r and through the T r' into the pipes v, leading to the caps or covers Y of the crank-shaft pedestals L. The pipes v are provided with the coupling x, secured to the box or chamber m², which is provided on each side with a parallel motion, consisting of the pipes h² and couplings i², to compensate for the vertical movements of the cross-head X of the piston-rods E and G. The oil or lubricant is forced by the action of the pump h through the pipes h² and couplings i² into the cross-head pins b² on one side to lubricate the same 100 and from whence it is forced out on the other side by the action of the pump h and down the pipes z, leading to the crank-pins. The oil or lubricant also passes up the pipe s² and through the aperture v³, from whence the 105 slides V are lubricated. The surplus oil or lubricant, which flows back to the oil well or reservoir f, is used over and over again as long as the engine is in motion. For lubricating the eccentrics N each end of the pipe v is provided with the pipe v⁴.

The pipes for conveying oil or lubricant are fitted with union joints and couplings where necessary for the purpose of fixing or removing the same when desired or necessary.

If desired, the engine may be provided with what is known as a "crank-shaft governor"

Z', (shown in Fig. 4 of the drawings,) or any other suitable governor may be employed for operating a throttle-valve. In case an ordinary ball or other governor is employed for controlling the speed of the engine it may be fixed in any desired position and driven by bands or ropes from the grooves a^6 on the end of the crank-shaft K.

Having now particularly described and ascertained the nature of my said invention and in what manner the same is to be performed, I declare that what I claim is—

1. The combination with the framework having oil-reservoir, of the crank-shaft, a pump located in said reservoir, an eccentric on said shaft connected with the pump, pipes leading from the pump to the parts to be lubricated, couplings on said pipes and branches leading therefrom to other parts to be lubricated the cross-head and slide-blocks having

oil-passages and means for carrying the surplus oil back to the reservoir, as set forth.

2. The combination with the framework having oil-reservoir, of the crank-shaft, a pump located in the reservoir and operated from said crank-shaft, pipes leading to the parts to be lubricated and supplied from said pump, the cross-head having pin with oil-passage, the slide-blocks having oil-passage, a return-pipe connected therewith, and means for compensating for the movements of the cross-head, substantially as specified.

In testimony whereof I have hereunto set my hand in presence of two subscribing witnesses.

WALTER MARTIN MUSGRAVE.
